UNITED STATES PATENT OFFICE.

BENJAMIN ALLEN, OF NEW BRITAIN, CONNECTICUT.

POCKET-KNIFE.

1,213,138.

Specification of Letters Patent. Patented Jan. 23, 1917.

Application filed August 21, 1916. Serial No. 116,035.

To all whom it may concern:

Be it known that I, BENJAMIN ALLEN, a citizen of the United States, residing at New Britain, in the county of Hartford and State 5 of Connecticut, have invented certain new and useful Improvements in Pocket-Knives, of which the following is a specification.

My invention relates to improvements in pocket-knives, and the object of my improvement is simplicity and economy in construction and convenience and efficiency in use.

In the accompanying drawing:—Fig. 1 is a side elevation of my improved pocket-knife. Fig. 2 is a view of the other side of 15 the same. Fig. 3 is a plan view of the same. Fig. 4 is a plan view of the blank for the handle. Fig. 5 is a sectional view on an enlarged scale on the line $x-x$ of Fig. 1. Fig. 6 is a plan view on the same scale as Fig. 1 20 of a pocket-knife embodying my invention provided with two blades. Fig. 7 is a sectional view on the same scale as Fig. 5 on the line $y-y$ of Fig. 6.

My improved pocket-knife comprises a 25 handle 10, a blade 11, and means for operatively holding the same together consisting of a rivet 12 and a slide 13 mounted on one end of the said rivet 12.

The blade 11 is ordinary and may have 30 any style of form and size as desired, and comprises a head 14 of the usual form at the end that is joined to the handle 10, the said head 14 comprising a generally straight edge 15 on the side of the cutting edge 16, substantially in parallelism therewith, and off-set slightly outwardly relatively to the same; a straight edge 17 at the extreme inner end, extending across the axis; a straight edge 18 parallel with the first mentioned straight 35 edge 15 and off-set inwardly relatively to the back edge 19 and connected to the said back edge 19 by a shoulder 20; and having a hole for the pin 12 in the portion bounded by the said straight edges 15, 17, and 18. 40 The edges 15 and 18 extend longitudinally of the blade and are substantially parallel with the axis.

The handle 10 is formed of a single piece 45 of sheet material, the blank therefor, as shown in Fig. 4, comprising at one end, shown at the left in the said figure, the handle side 21, being the side that is in the rear in Fig. 1, and at the right end the front handle side 22, the said sides 21 and 22 being 50 connected at the middle of the blank by the neck 23, as shown slightly reduced relatively

to the said sides, and having a flange-like projection 24 connected to one of the lateral edges of the said right or front handle side 22, adjacent the outer end thereof.

The left or rear handle side 21 is provided with a hole 25 adjacent the outer end for the pin or rivet 12 and the right or front handle side 22 has a transverse slot 26 adjacent the outer end that is a fit for the said rivet 12. 60 The flange 24 is turned inwardly along the line 27, that is coincident with the back edge 28 of the handle side 22 suitably to extend across the back portion of the handle structure so as to coöperate with the various edges 65 of the head 14 of the blade 11, for holding the blade in the usual different positions, comprising the closed, half open, and full open positions. Thus the flange 24 is of sufficient length to engage with the straight 70 edge portion 15 that is parallel with the cutting edge 16, which is the longest of the edges that bound the head 14 and comprises a slight excess of length, and fills a portion 75 only of the rear of the handle structure, the remainder of the said rear being open.

The handle sides 21 and 22 are shaped to provide the desired contour of the handle structure and the blank is folded along two transverse lines 29 at the junctions of the sides 80 21 and 22 with the neck 23, the said lines 29 being spaced suitably to provide the proper thickness or depth for housing the blade 11, the sides 21 and 22 being brought into parallelism, with the slot 26 opposed to the hole 85 25.

The rivet or pin 12 has the rear end positioned in the hole 25 and headed over, the body portion extending through the blade 11 and through the slot 26, and the front end 90 extending through a hole in the slide 13 and being headed over suitably to hold the said slide 13 in sliding engagement with the outer face of the front handle side 22.

The slide 13 serves as a button or cap to 95 cover the slot 26 and to hold the handle 10 and the blade 11 operatively connected.

The neck 23 serves to fixedly connect the handle sides 21 and 22 generally and at the same time because of the resiliency of the 100 material of which the blank is formed, serves to resiliently connect the said sides, permitting of relatively lateral movement of the two sides, one side moving slightly to one side relatively to the other responsive to pressure, the neck 23 yielding to such pressure. Thus 105 the neck 23 serves as the equivalent of a 110

hinge or pivotal connection for the handle sides, permitting the same to be moved in substantial parallelism to the extent necessary to permit the blade 11 to be shifted 5 from one position to the other and serves as a spring to hold the parts in resilient engagement as is usual in pocket-knives. The neck 23 is hardened and tempered suitably to serve as a spring as described.

10 The rivet 12 travels in the slot 26 as the handle sides 21 and 22 are moved in the manner described.

Instead of having only a single blade 11 I may use two blades 11^a and 11^b mounted on 15 the same rivet 12^a, both of which may be formed and operated as in the case of the said blade 11.

By having the bridge or neck 23 appreciably narrower than the width of the handle 20 sides 21 and 22 as shown, that is to say, the neck 23 being reduced as mentioned, relatively to the adjacent portions of the handle sides 21 and 22, I find that the proper spring effect is obtained for satisfactory operation 25 and at the same time I am permitted to incorporate certain features that are desirable and are found generally in ordinary knife structures. For instance, the corners of the handle sides adjacent the neck 23 can be ap- 30 preciably rounded, as shown, thus presenting the appearance of a knife of ordinary structure. Also the end of the handle is closed, as in the case of an ordinary knife. Of particular importance however is the fact

that the neck or bridge serves as a positive 35 spacer for spacing the handle sides suitably to insure an open space for housing the blade in the closed position, thus permitting the free opening and closing of the blade, by preventing the closing of the handle sides 40 over the blade receiving space when the blade is open and preventing the handle sides from being forced against the blade and pinching the same when in the closed position. 45

I claim as my invention:—

In combination in a pocket knife having a handle formed of a single piece of sheet material and a blade, the said blade being operatively connected to one end of the handle structure, and the said handle structure comprising a pair of handle sides opposed one to the other and separated by a blade receiving space, the said blade filling the said space at one end of the said handle 50 sides, means for holding the other ends of the said handle sides in spaced relation comprising a bridge extending across the end portions of the said handle sides, and the said bridge serving as a spring member for 55 resiliently holding the said blade in the position to which it is set relatively to the said handle. 60

BENJAMIN ALLEN.
